TYPEWRITING MACHINE

Bernard Joseph Dowd, West Hartford, Conn.,
assignor to Royal Typewriter Company, Inc.,
New York, N. Y., a corporation of New York

Application October 1, 1938, Serial No. 232,863

6 Claims. (Cl. 197—102)

This invention relates to typewriting machines, and more particularly to typewriter keys. Keys embodying the invention may, however, be applied to finger-operated members of other machines, such as adding machines, computing machines and the like.

One type of key in general use includes a cup or base part supporting a disk of cardboard or the like displaying a character and being covered with a disk or ordinary glass positioned to protect the character and to be engaged by the operator's fingers. An objection to covering disks formed of glass is that the glass is susceptible to breakage both during assembly of the key and in use. Furthermore, as a material, glass is practically inflexible and is not well adapted for molding or cutting in small units to form disks of special design.

As substitutes for the usual glass disks and in attempts to overcome the disadvantages inherent in glass disks, key cover disks also have been made of Celluloid and other molded substances, but such disks have been found to have other disadvantages. One principal disadvantage of molded materials heretofore used has been their susceptibility to becoming scratched, whereby their transparency has been impaired, not only rendering it more difficult to see the character, but giving the entire keyboard a dingy appearance.

An object of the invention is to provide a typewriter key character-cover disk having improved properties and in which the disadvantages of key cover disks heretofore known are eliminated.

In accordance with one feature of the invention, a typewriter key is provided with a cover disk of molded plastic material possessing advantages not heretofore known or appreciated as making it especially efficient and serviceable when used in typewriter keys. The material found most satisfactory is methyl methacrylate plastic, preferably such material known by the proprietary name, "Lucite." This material is crystal clear, so clear that it is possible to read news print through a thick block of it. It is considerably more clear and transparent than other plastics.

It is only about half as heavy as common glass, is somewhat flexible, non-shattering, strong and durable, and is not readily scratched. Sunlight does not affect its clearness or color; it is unaffected by most chemicals, and is substantially non-hygroscopic. It is superior to Celluloid and cellulose acetate materials in that its surface is harder, being thereby less easily scratched, it is

more transparent, it will not discolor, and it is substantially non-inflammable. A surprising property rendering it particularly serviceable for cover disks for typewriter keys is that the material is polishable by the normal touch of the operator's fingers during typing, so as to have its transparency and crystal clearness thereby maintained substantially unimpaired.

Another object is to provide a typewriter key assembly of novel and improved construction.

A further object is to provide a typewriter key assembly of novel construction adapting it especially for the incorporation therein of a transparent cover disk of somewhat flexible material. Other objects will become apparent from a reading of the following description, the appended claims and the accompanying drawing in which:

Figure 1 is a vertical sectional view of one embodiment of the invention, the section being taken on the line 1—1 of Figure 2;

Figure 2 is a bottom plan view looking in the direction of the arrows 2—2 in Figure 1;

Figure 3 is a view similar to Figure 1 but showing a modification;

Figure 4 is a similar view showing another modification;

Figure 5 is a similar view of a further modification; and

Figure 6 is a top plan view of the assembly shown in Figures 1 and 2 and drawn on a smaller scale.

Among the several constructional forms of the invention shown for the purposes of illustration, Figures 1 and 2 show a portion only of a key lever A, which may be of usual form, and which serves to mount a key assembly generally designated B. The key assembly includes a cup C having a bottom or base 1 and an annular side wall 2. A washer 3 disposed within the cup is provided with a slot 4 registering with a slot 5 in the base of the cup, the two slots receiving a key lever shank 6 which is peened out as at 7 to secure the key lever, cup, and washer in assembled relation. The washer is formed with opposed raised flanges 8 serving a purpose to be described.

A disk 9 of cardboard or the like displaying a character 10 on its upper face is positioned within the cup so as to rest upon the flanges 8. A transparent disk 11, preferably and in accordance with one feature of the invention being as described and having the properties and characteristics referred to above, is positioned over the character disk 10 and protrudes slightly above the cup side wall 2.

A key cap 12 is provided for holding the trans-

parent disk down against the character disk 9 and the latter against the washer flanges 8. In the form shown in Figures 1 and 2 the key cap includes a rim 13 adapted to fit the cup wall 2 and an inwardly turned flange 14 overlying the marginal portion of the transparent disk 11. In order that the key will present a neat appearance and a smooth surface for the touch of the operator's fingers, the upper marginal part of the disk 10 is recessed as at 15 in such manner as to receive the cap flange 14 so that the top of the flange will be flush with the top surface of the disk 11.

The parts may be held in assembled relation by ears 16 formed integrally with the cap 12 and turned under the bottom of the cup. The transparent disk 11 is of uniform thickness, having a concave top surface and a convex bottom surface. An additional advantage of the material described above is that it can readily be molded 20 in forms such as that shown in Figure 1. The washer flanges 8-8 serve to support the character disk 9 and the transparent disk 11 held down by the cap 12, and prevent the parts from becoming loose and rattling after long use. Preferably the flange 14 is slightly yieldable so that the parts may be held under a continued compressive force after the ears 16 have been turned under the cup. Since the transparent disk 11 itself is somewhat flexible, there is no danger of 25 breaking it when placing the parts under compression during assembly. Thus, the characteristics of the disk 11 and the yieldability of the flange 14 contribute to the making of a firm, permanently tight assembly.

35 In the embodiment shown in Figure 3 the key lever A, cup C^a and washer 3 are the same as the corresponding parts in the Figure 1 embodiment, with the exception that the annular side wall 2^a of the cup shown in Figure 3 is relatively 40 more shallow than the wall 2 of the cup shown in Figure 1. The transparent disk 11^a differs from the disk 11 in the Figure 1 form in that its bottom face is flat instead of convex, the character disk 9^a also being flat. The peripheral edge portion of the disk 11^a is beveled upwardly and inwardly as at 15^a instead of being angularly recessed, and extends over the annular wall 2^a of the cup. In the Figure 3 modification, a key cap 12^a having a rim 13^a fitting the cup is provided 45 with an inwardly turned somewhat flexible flange 14^a, the extreme inner edge of which is tapered off in thickness so that the bottom of the tapered edge portion will lie snugly against the beveled periphery 15^a of the disk 11^a, and the top of the 50 flange inner edge will be substantially flush with the top of the disk 11^a. Ears 16^a on the cap 12^a bent in under the bottom 1^a of the cup, hold the parts together firmly. The key assembly B^a thus 55 provided possesses the particular advantage that it is not necessary to maintain extremely precise or close tolerances in the dimensions of the transparent disk and the key cap in order to provide a neat, permanently strong assembly. Thus, if the diameter of the inner edge of the flange 60 14^a is slightly greater than the diameter of the upper peripheral edge of the transparent disk 11^a, the tapered portion of the flange 14^a still will lie snugly against the beveled edge 15^a of the disk, and in the assembled key, any small discrepancy 65 in dimensions of the component parts will not be discernible.

70 In the form shown in Figure 4 the construction and arrangement of the parts is the same as in the Figure 3 embodiment with the exception that in the Figure 4 form, the transparent disk

11^b, provided with a beveled peripheral edge 15^b, is convex on its bottom face, and the character disk 9^b is curved or dished accordingly. Otherwise the parts of the Figure 3 assembly B^a and the Figure 4 assembly B^b are similar and are 5 designated by corresponding reference characters.

The assembly B^c, shown in Figure 5, is generally similar to the assembly shown in Figure 4, and corresponding parts are designated by similar reference characters in the two figures. The Figure 5 form differs from the Figure 4 form in that the transparent disk 11^c, shown in Figure 5, fits within the annular cup wall 2^c instead of over the cup wall as in Figure 4, and the upper portion 15 only of the periphery of the disk 11^c is beveled at 15^c, the lower portion being substantially perpendicular to the cup bottom 1^c and being fitted within and centered by the cup wall 2^c.

In all three assemblies B^a, B^b and B^c shown in Figures 3, 4 and 5, respectively, the yieldability of the key cap flanges and the non-shattering property of the material forming the transparent disks makes it possible to press the parts firmly together in assembling without danger of breaking or chipping the transparent disks. However, transparent cover disks formed of the material described and possessing the characteristics and properties specified above may be embodied in various key assembly constructions. Some other 30 forms of key assemblies which may include transparent disks of material as described herein are disclosed and claimed in the copending application of William O. Michelsen, Serial Number 232,888, filed October 1, 1938. The forms disclosed are preferred, but changes may be made in the construction and arrangement of the parts without departing from the invention as defined in the claims.

40 I claim:

1. In a key of the character described, a key cup equipped to display a character; a transparent cover disk supported by the cup and through which the character is viewable, said disk having a beveled peripheral edge portion; 45 and a disk-retaining key cap ring including a rim fitted to said cup and an inwardly turned flange contacting the upper inner portion only of the beveled peripheral edge portion of said disk.

2. In a key of the character described, a key cup equipped to display a character; a transparent cover disk supported by the cup and through which the character is viewable, said disk having a beveled peripheral edge portion; 55 and a disk-retaining key cap ring including a rim fitted to said cup and an inwardly turned flange, the extreme inner edge portion of said flange being tapered off in thickness with the bottom of the tapered portion contacting the upper inner portion only of the beveled peripheral edge portion of said disk, and the top of said flange inner edge portion lying substantially flush with the marginal portion of said disk.

3. In a key of the character described, a key cup equipped to display a character; a transparent cover disk supported by the cup and through which the character is viewable, said disk having a beveled peripheral edge portion; 70 and a disk-retaining key cap ring including a rim fitted to said cup and an inwardly turned flange contacting the upper inner portion only of the beveled peripheral edge portion of said disk, the periphery of said disk being disposed above the 75

periphery of the cup and concentrically within the cap rim.

4. In a key of the character described, a key cup equipped to display a character; a transparent cover disk supported by the cup and through which the character is viewable, said disk having a beveled peripheral edge portion; and a disk-retaining key cap ring including a rim fitted to said cup and an inwardly turned 10 slightly yieldable flange contacting the upper inner portion only of the beveled peripheral edge portion of said disk.

5. In a key of the character described, a key cup equipped to display a character; a transparent cover disk supported by the cup and through which the character is viewable, the lower part of the peripheral edge of the disk being substantially perpendicular to the bottom of the cup and the upper part of said peripheral 15 edge being beveled upwardly-inwardly; and a disk-retaining key cap ring including a rim fitted to said cup and an inwardly turned flange contacting the upper inner portion only of said bevel-

eled edge part, said lower edge part of the disk being disposed within the cup and said beveled upper edge part extending above said cup, said cap flange being disposed above and out of contact with the uppermost part of the cup. 5

6. In a key of the character described, a key cup equipped to display a character; a transparent cover disk supported by the cup and through which the character is viewable, said disk having a beveled peripheral edge portion; and a disk-retaining key cap ring including a rim fitted to said cup and an inwardly turned flange contacting the upper inner portion only of the beveled peripheral edge portion of said disk, the extreme inner edge portion of said 15 flange being tapered off in thickness, the top of said flange inner edge portion lying substantially flush with the marginal portion of said disk, and the bottom of said flange inner edge portion substantially conforming to and lying against the 20 beveled peripheral edge portion of said cover disk.
